UNITED STATES PATENT OFFICE.

ROBERT LEE SOUTHERN, OF LOS ALTOS, CALIFORNIA, ASSIGNOR TO ARLEES MOTORS INCORPORATED, OF PALO ALTO, CALIFORNIA, A CORPORATION OF NEVADA.

ENGINE.

Application filed July 13, 1927. Serial No. 205,421.

This invention relates to an internal combustion engine, the general object of the invention being to provide an engine so constructed that it will have great power, high speed and the maximum efficiency, with the minimum consumption of fuel.

Another object of the invention is to provide means for forcing a supply of compressed fuel and air into the various cylinders by means of valve controlled ports so that the combustible mixture is compressed as it enters the cylinders, where it is further compressed by the pistons, with means for firing the charge in each cylinder once on every revolution of the shaft, with suction means for drawing the exhaust gases from the cylinders.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a diagrammatic plan view of the engine.

Figure 2 is a section on line 2—2 of Figure 1.

Figure 3 is a section on line 3—3 of Figure 1.

Figure 4 is a fragmentary side view.

Figure 5 is a view of one of the valves.

Figure 6 is a view of one of the cams.

Figure 7 is a sectional view through the hand operated device for closing the circuits to the various cylinders.

Figures 8 and 9 are sectional views through the shaft.

Figure 10 is a diagrammatic view of the circuits.

In these drawings, 1 indicates a plurality of uprights supported from a suitable base and having bearings 2 at their upper ends for rotatably supporting a shaft 3. This shaft has connected thereto or formed therewith a plurality of blocks 4 of rectangular shape and each block carries a number of cylinders 5, a cylinder being arranged on each face of the block. The cylinders are bolted to the blocks. As shown, one of these cylinders

carrying blocks is arranged between each pair of supports and a pair of stationary gears 6 is connected to each support adjacent each block. A piston 7 is located in each cylinder and the piston rod 8 is connected to a small crank shaft 9 supported by the bearings 10 which are fastened to the end of an adjacent cylinder and each shaft has fastened to each end thereof a gear 11 which meshes with the stationary gear 6. These gears are of the spiral type. Thus each block carries four cylinders with the pistons therein, the pistons acting to rotate the crank shafts and the eight gears 11, which mesh with the stationary gears 6 so that the gears 11 must revolve around the gears 6 and thus the shaft 3 and the cylinder carrying blocks will rotate as the pistons are being reciprocated in the cylinders.

The shaft 3 is provided with a central bore 12 which terminates adjacent the last block, and each block is provided with four passages 13 which connect this bore with the cylinders carried by the block. The forward end of the shaft, through which the bore passes, is connected to a supply pipe 14 by a coupling 15 which permits rotary movement of the shaft 3, and this pipe 14 is connected to a tank 16 into which a compressed mixture of fuel and air is forced from a carburetor 17 by a compressor 18. Thus the explosive mixture is introduced into the cylinders in a compressed state.

That part of the shaft which carries the blocks 4 is enlarged and is formed with four exhaust passages 19, and each block is formed with four exhaust passages 20, each of which connects a passage 19 with a cylinder. These exhaust passages 19 merge into a single passage 19' at the rear end of the shaft which leads the exhaust gases to a fan casing 21, the fan 22 of which is connected with the end of the shaft so that when the engine is in operation, a suction will be created in the exhaust passages which acts to draw the exhaust gases from the cylinders through the passages in the shaft into the casing 21, from which it escapes through the discharge outlet 23 of the casing. The inlet and exhaust passages leading to each cylinder are controlled by a sliding valve 24 which fits in a groove 25 formed in the inner wall of each cylinder, said valve having a port 26 therein which controls the inlet and exhaust passages 13 and 20. Each valve is provided with a bent outer end which

carries a roller 27 and a spring 28 holds this roller against a cam 29 fastened to the hub of one of the gears 11, the spring 28 being located in the groove 25. Thus the valves are 5 actuated to open and close the inlet and exhaust passages by the rotary cams on the crank shafts.

The charge in each cylinder is fired by means of the spark plug 29, carried by each 10 cylinder coming in engagement with the spring contact 31 carried by the arm 32 of insulating material which is fastened to the top of the support 1, and this contact is connected to a source of supply by the conductor 33. 15 The charge will be fired when the cylinder reaches its top position so that the cylinders of each block will be fired once every revolution of the shaft.

As shown in Figures 2 and 3, the piston of 20 each cylinder reaches the limit of its compression stroke when the cylinder is in its top position, and just at this time the spark plug comes in engagement with the contact 31 so that the charge is fired. The piston then 25 starts on its power stroke, the valve remaining closed until the piston reaches the limit of its power stroke or practically so, when the valve uncovers the exhaust passage so that the exhaust gases can escape from the cylinder. 30 Then the piston starts its compression stroke and just before this, the valve uncovers the inlet passage so that a charge of compressed mixture will enter the cylinder and then this charge is further compressed by the forwardly moving piston. The valve remains 35 closed from this point until it is moved to exhausting position, for during the compression stroke, and the power stroke, the roller on the cam engages the concentric part of the cam and thus the valve remains in closed position. When the roller engages the high 40 part of the cam, the valve is moved to a position to open the exhaust port and then when the roller passes over the low part, the valve 45 is moved by the spring to a position to open the inlet port.

I provide means whereby some of the groups of cylinders can be rendered inactive by opening their ignition circuits so as to 50 prevent the charges being fired in the cylinders. As shown in Figures 10 and 7, such means comprises a casing 34 carrying the terminals 35 which are arranged in three groups, one group having six terminals therein, the 55 other group four terminals and the third group two terminals. The terminals of the large group are each connected with a contact 31, the four terminals of the second group being connected with four of the contacts 31 and the two contacts of the third group being connected with two of the contacts 31.

A cylinder 36 is rotatably mounted in the casing and carries a strip 37 which is electrically connected by the contact 38 with a

source of supply. The cylinder is provided with a stem 39 to which is secured a knob 40 so that the cylinder can be turned by hand. When the strip 37 is in engagement with the first group of terminals, all of the contacts 70 31 will be connected to the source so that all the cylinders of the engine will be fired as the shaft rotates. When the cylinder is turned to place the strip 37 in engagement with the group containing four terminals, but four 75 of the contacts 31 will be connected with the source so that the cylinders of but four of the sets will be firing, the other two sets being idle. When the cylinder is turned to place the strip 37 in engagement with the group containing two of the terminals 35, but two of the sets of cylinders will be firing while the other four sets will be idle. Thus the engine can be controlled to make it operate with more or less power as desired by adjusting the cylinder. 80

A gear 41 is mounted on the rear end of the shaft 3 and this gear is in mesh with a pinion 42 arranged on a shaft 43 and with a gear 44 arranged on a hollow shaft 45. The shaft 43 has loosely mounted thereon a gear 46 which is adapted to be connected with the shaft by the clutch means 47.

This gear 46 meshes with a pinion 48 attached to a driven shaft 49. This driven shaft carries the gears 50 and 51. The shaft 45 is formed with a square bore to receive a square part of shaft 54 which passes through the shaft 45. A pinion 52 is loosely mounted on the shaft 54 and meshes with the gear 50 and the clutch means 53 is provided for connecting the pinion 52 with the shaft 45. The shaft 54 has loosely mounted thereon the pinion 55 which is adapted to be connected with the shaft 54 by the clutch 56. An idle pinion 57 is placed between the pinion 55 and the gear 51. 100

Thus it will be seen that when the shaft 49 is to be driven at high speed from the shaft 3, the clutch 47 is moved into operative position so that the drive will be from the gear 41 through pinion 42, shaft 43, clutch 47, gear 46, pinion 48 to shaft 49, the other gears and pinions idling. When the shaft 49 is to be driven at low speed, the clutch 53 is moved into operative position so that the drive will be from gear 41, gear 44, shaft 45, clutch 53, pinion 52, gear 50 to shaft 49. When the shaft 49 is to be driven in a reverse direction from that of shaft 3, clutch 56 is moved to operative position so that the drive will be from gear 41 to gear 44, shaft 45, clutch 56, pinions 55 and 57 and gear 51 to shaft 49. 110

A generator 58 is attached to the forward 125 end of the shaft 3 to generate current for the ignition means and lighting means, if desired.

By having the means for supplying a compressed mixture to the cylinders, the cylin- 130

ders will be kept full of the mixture under compression so that when the engine is to be started, it is simply necessary to close the ignition means when those cylinders that are 5 in firing position will be fired and thus start the engine in motion, though if desired, the usual self-starter may be provided for the engine.

Any suitable oiling system can be used for 10 oiling the various parts, and if desired, a vacuum tank can be connected with the exhaust passages 19' to help the fan exhaust the products of combustion from the engine.

I also provide a cooling system which consists in making the spokes of the gears 11 in 15 the form of fan blades, as shown at 59, and in forming openings 60 in the blocks 4 adjacent the cylinders thereon so that the air thrown off by the revolving blades 59 will 20 pass through these openings and will strike the walls of the cylinders and thus cool the parts which are subjected to heat. If desired, the cylinders may be provided with fins.

While the drawings show the engine 25 formed of three units, each unit consisting of two blocks and their cylinders, it will, of course, be understood that it may be formed of any desired number of units. As each cylinder fires once on every revolution of the 30 engine, there will be eight firing impulses of every unit to one revolution of the main shaft.

It is thought from the foregoing description that the advantages and novel features 35 of my invention will be readily apparent.

I desire it to be understood that I may make changes in the construction and in the combination and arrangement of the several parts, provided that such changes fall within 40 the scope of the appended claims.

What I claim is:—

1. An engine of the class described comprising a rotatably supported shaft, a plurality of cylinder blocks carried by the shaft, 45 a cylinder on each face of each block, a piston in each cylinder, a crank shaft on each cylinder to which the piston of another cylinder is connected, gears on each crank shaft, a pair of stationary gears supported adjacent each block and with which the gears of each block mesh so that rotary movement will be 50 imparted to the shaft and the blocks by the movement of the gears, under the action of the pistons, around the stationary gears, the main shaft having a passage therein and the blocks having ports therein connecting the passages with the cylinders, means for connecting the passage with a supply of combustible mixture, the shaft having exhaust passages 55 therein and the blocks having exhaust ports connecting the passages with the cylinders, exhaust means connected with the exhaust passages in the shaft, a valve in each cylinder for controlling the exhaust and inlet ports thereof, cams on the crank shafts for actuating 60 said valves, a spark plug in each cylinder, a spring contact adjacent each group of cylinders and adapted to be engaged by the spark plug of each cylinder when the cylinder reaches a certain position and means for connecting the spring contacts with a source of 65 supply.

2. An engine of the class described comprising a rotatably supported shaft, a plurality of cylinder blocks carried by the shaft, a cylinder on each face of each block, a piston in each cylinder, a crank shaft on each cylinder to which the piston of another cylinder is connected, gears on each crank shaft, 70 a pair of stationary gears supported adjacent each block and with which the gears of each block mesh so that rotary movement will be 75 imparted to the shaft and the blocks by the movement of the gears, under the action of the pistons, around the stationary gears, the main shaft having a passage therein and the blocks having ports therein connecting the passages 80 with the cylinders, means for connecting the passage with a supply of combustible mixture, the shaft having exhaust passages therein and the blocks having exhaust ports connecting said passages with the cylinders, 85 valves for controlling the exhaust and inlet ports, means for actuating the valves from movable parts of the engine, ignition means for the cylinders, manually operated means for controlling the ignition circuit of the 90 groups of cylinders so as to permit all the cylinders to be fired or to permit certain groups of cylinders to be fired while the others remain idle and transmission means connected with the shaft. 95

3. An engine of the class described comprising a plurality of supporting means, a shaft rotatably supported by such means, a plurality of rectangular blocks carried by the shaft, a cylinder on each face of each block, 100 a piston in each cylinder, a crank shaft on each cylinder with which the piston rod of an adjacent piston is connected, gears carried by each crank shaft, a plurality of pairs of stationary gears on the supporting means, 105 each pair of gears being arranged adjacent a block so that the gears of each block will mesh with said pair of stationary gears, the main shaft having a passage therein, ports in the blocks connecting the passage with the cylinders, means for connecting the passage with a supply of combustible mixture under compression, the shaft having exhaust passages 110 therein and the blocks having exhaust ports connecting the passages with the cylinders, 115 exhaust means connected with the exhaust passages in the shaft, a valve in each cylinder for controlling the exhaust and inlet ports thereof, cams on the crank shafts for actuating said valves, a spark plug in each cylinder, 120 a spring contact adjacent each group of cylinders and adapted to be engaged by the spark plug of each cylinder when the cylinder reaches a certain position and means for connecting the spring contacts with a source of 125 supply.

4. An engine of the class described comprising a plurality of supporting means, a shaft rotatably supported by such means, a plurality of rectangular blocks carried by 130

the shaft, a cylinder on each face of each block, a piston in each cylinder, a crank shaft on each cylinder with which the piston rod of an adjacent piston is connected, gears carried by each crank shaft, a plurality of pairs of stationary gears on the supporting means, each pair of gears being arranged adjacent a block so that the gears of each block will mesh with said pair of stationary gears, said main shaft having a passage therein, the blocks having ports therein connecting the passage with the cylinders, means for connecting the passage with a supply of combustible mixture under compression, the shaft having exhaust passages therein and the blocks having exhaust ports connecting the passages with the cylinders, exhaust means connected with the exhaust passages in the shaft, a valve in each cylinder for controlling the exhaust and inlet ports thereof, cam means on the crank shafts for actuating the valves,

a spark plug in each cylinder, a spring contact adjacent each group of cylinders and adapted to be engaged by the spark plug of each cylinder when the cylinder reaches a certain position, means for connecting the spring contacts with a source of supply, such means comprising a casing, a plurality of terminals therein arranged in groups, one group containing as many terminals as there are spring contacts and the other groups containing a less number of terminals, means for connecting the terminals with the spring contacts, a cylinder in the casing, means for turning the cylinder by hand and a strip carried by the cylinder and connected with a source of supply, said strip engaging any one of the groups of terminals when the cylinder is turned.

In testimony whereof I affix my signature.

ROBERT LEE SOUTHERN.
